UNITED STATES PATENT OFFICE

CHESTER R. STACKHOUSE, OF CADILLAC, MICHIGAN

DESIGN FOR A BASEBALL TARGET

Application filed August 15, 1932. Serial No. 44,608. Term of patent 3½ years.

To all whom it may concern:

Be it known that I, CHESTER R. STACKHOUSE, a citizen of the United States, residing in Cadillac, in the county of Wexford and State of Michigan, have invented a new, original, and ornamental Design for a Baseball Target, of which the following is a specification, reference being had to the accompanying drawing, forming part thereof, in which the figure is a plan view of the baseball target showing my new design.

I claim:

The ornamental design for a baseball target, as shown.

Signed at Cadillac, in the county of Wexford and State of Michigan, this 27th day of June, 1932.

CHESTER R. STACKHOUSE.
